TAMпон

William M. Knight, Minneapolis, Minn., assignor
to The Personal Products Corporation, Mill-
town, N. J., a New Jersey corporation

Application January 4, 1940, Serial No. 312,379

8 Claims. (Cl. 128—285)

This invention relates to new and useful improvements in tampons for the absorption of fluids given off by the body, and more particularly to catamenial tampons adapted for internal application to absorb and collect fluids discharged during menses, and to methods of making catamenial tampons.

Catamenial tampons must desirably be capable of absorbing and holding large quantities of fluids so that the time intervals between changes, when using catamenial tampons, is not materially greater than the time interval between changes, when using ordinary sanitary napkins. Tampons are usually worn internally, and for satisfactory use it is therefore, essential that they be relatively small and compact in size so as to facilitate insertion. At the same time, the tampon structure must be comfortable to the user, both during insertion and while in use, and must not assume an uncomfortable configuration during use, and must be non-irritating. It is also exceedingly desirable that the configuration of the tampon after complete fluid absorption, is such that it will retain its position in the vaginal canal without discomfort until removed therefrom.

An object of the present invention therefore, is to provide a catamenial tampon, in which all of the objectionable features now prevalent in commercial tampons have been eliminated, and which embodies all of the desirable features hereinbefore enumerated, and which is so constructed that the costs of manufacture will be exceedingly small.

A further object of the invention is to provide a catamenial tampon made of a suitable fibrous material, such as cotton, which is so arranged that substantially the entire exterior surface of the tampon is composed of cross fibers, or, in other words, of fibers disposed transversely to the axis of the tampon, whereby the absorption ability of the tampon is greatly increased.

A further object is to provide a tampon composed of two mats of fibrous material, the fibers of one of said mats being disposed in a direction lengthwise of the mat, and the fibers of the other mat being disposed crosswise thereof, and said mats being placed together in flatwise relation to provide an elongated body, said body being folded transversely to bring the opposite ends thereof into juxtaposition, after which said folded body is compressed into an elongated cylindrical body in such a manner that the long fiber mat will be disposed within the cross fiber mat, whereby substantially the entire exterior surface of the tampon will be composed of fibers disposed

transversely to the axis of the tampon, thereby greatly increasing the fluid absorptive ability of the tampon, and the long fibers of the mat which is concealed within the tampon further increasing the fluid absorbent capacity of the tampon, in addition to providing a support for the cross fibers and adequate tensile strength in the tampon to insure complete removal of the tampon, when withdrawn by manipulation of the usual cord, which is attached to the concealed longitudinally extending fibers of the inner mat of the tampon.

A further object of the invention is to provide a tampon of fibrous material which is sufficiently dense and hard, when dry, as before use, to facilitate packaging and sterilization, and also to facilitate handling such as may occur when the tampon is carried in a pocket or ladies' handbag, and lastly, to facilitate insertion of the tampon into the vagina.

A further object is to provide a tampon of the character described, which is relatively small and compact, when dry, but which is capable of expansion in size diametrically, when wetted or subjected to the body fluids, so as to facilitate retention of the tampon in the vagina, even though the wearer stands, walks, dances, or otherwise exercises.

Other objects of the invention are to provide a tampon which is capable of expanding progressively from top to bottom, and which is capable of absorbing and retaining relatively large quantities of fluid over an extended period, without danger of the tampon accidentally becoming dislodged from the vagina; which is so constructed that there is no danger of fluid flow or leakage through the tampon, even though changing of the tampon may be delayed, and which is provided with a cord or string for withdrawal of the tampon from its package, and for withdrawal and handling of the tampon after use, which cord is firmly attached to the mats of fibrous material constituting the tampon, such cord projecting from one end of the tampon whereby it cannot cause any irritation, when the tampon is in use; and in the novel method of forming the tampon of two mats of fibrous material or cotton, placed together in flatwise relation, and the fibers of one mat running lengthwise thereof and the fibers of the other mat being transverse to the length of the tampon and forming the exterior thereof.

Other objects of the invention will appear from the following description and accompanying drawing and will be pointed out in the annexed claims.

In the accompanying drawing there has been

disclosed a structure designed to carry out the various objects of the invention, but it is to be understood that the invention is not confined to the exact features shown as various changes may be made within the scope of the claims which follow.

In the drawing:

Figure 1 is a view showing the two mats placed together in flatwise relation with the cord coiled thereabout;

Figure 2 is a view showing the cord partially tightened;

Figure 3 is a view showing the elongated body formed by the two mats partially folded upon itself;

Figure 4 is a view showing the folded body being drawn into a forming die;

Figure 5 is a plan view of Figure 4;

Figure 6 is a vertical sectional view on the line 6—6 of Figure 7, showing a partially completed tampon being forced through the forming die;

Figure 7 is a sectional plan view on the line 7—7 of Figure 6;

Figure 8 is a view showing the completed tampon with the cord attached to one end thereof; 25 and

Figure 9 is a cross-sectional view on the line 9—9 of Figure 8, showing the long fibers substantially concealed by the cross fibers.

In the formation of the novel tampon herein disclosed, two mats of fibrous material, designated by the numerals 2 and 3, are placed together in flatwise relation, as shown in Figure 1. The mat 2 is composed of long fibers running longitudinally thereof, whereas the mat 3 has its fibers running crosswise to its length. By this arrangement, it will be noted that the fibers of the two mats are arranged in substantially right angular relation, when the two mats are placed together to form the body, generally indicated by the numeral 4.

A cord 1 is then coiled about the body 4, as shown in Figure 1, and when drawn tightly about said body, partially folds the mats along a longitudinal axis, whereby the cross fibers of the mat 3 partially encircle the long fibers of the mat 2 at the intermediate portion of the body 4, as will be noted by reference to Figure 2. The body 4 is then folded upon itself to bring the end portions of the mat 3 into contiguous relation, and the opposite ends of the body 4 into juxtaposition, as best shown in Figure 4.

To compress the folded mats into a cylindrical body, the folded mats are forced through a cylindrical bore provided in a suitable forming die, generally designated by the numeral 5. The diameter of the bore 6 determines the diameter of the finished tampon 7, shown in Figure 8.

A feature of the invention resides in the novel construction of the forming die, whereby when the folded mats or body 4 is drawn or forced through the bore 6 thereof, the long fibers of the mat 2 are brought to the inside and are substantially completely surrounded by the short fibers of the mat 3. To thus cause the short cross fibers of the mat 3 to be brought to the outside of the tampon, oppositely disposed blades 8 are suitably fixed in slots 9 provided in the body of the die 5. The inwardly facing edges of the blades 8 are preferably curved, as best shown in Figures 3, 4, and 6, and project into the bore 6, with their adjacent points spaced apart to receive the intermediate portion of the folded body 4. The blades 8 cooperate to compress the folded body 4 along its longitudinal centerline, as

best shown in Figure 5, whereby oppositely disposed end portions of the folded body 4 are folded along their longitudinal axes. As the body 4 is pulled or forced downwardly into the bore 6 between the adjacent edges of the blades 8, the long fibers of the mat 2 become firmly folded against opposite sides of the blades 8, and as the folded body 4 continues its downward movement in the bore 6, the short cross fibers of the mat 3 substantially completely surround the long fibers of the mat 2, whereby when the tampon is completed, as shown in Figures 8 and 9, the exterior cylindrical surface thereof will be constituted substantially entirely of short, cross fibers, disposed substantially at right angles to the body of the cylindrical tampon 7, as shown in Figure 8.

In forcing the folded body 4 through the forming die, it may initially be pulled into the bore 6 by manipulation of the cord 1, until it reaches substantially the position shown in Figure 4, after which it may be forced through the bore 6 by a suitable plunger 11, shown having a concaved lower end 12 adapted to engage the upper end of the folded body 4 and force it through the bore 6, whereby the two mats are compressed into a cylindrical body to form the completed tampon 7. The plunger 11 has oppositely disposed slots 13 for receiving the blades 8, when the plunger enters the bore 6 of the forming die 5.

In actual practice it has been found that the novel tampon herein disclosed may be expeditiously formed in the manner above described. The mats 2 and 3 may be cut to suitable size by suitable dies and are placed together in flatwise relation, as shown in Figure 1, in the initial operation of forming the tampon. In the next step, the cord 1 is attached to the body 4, after which the body is passed through the bore 6 of the forming die 5, as hereinbefore stated, to complete the formation of the tampon.

The method of forming this tampon is very simple and inexpensive and makes it possible to manufacture the tampons in quantity production at exceedingly low cost.

One of the outstanding features of the invention, as previously stated, resides in the unique manner of folding the mats 2 and 3 from the position shown in Figure 1, whereby when the tampon has been completed, as shown in Figures 8 and 9, the long fibers of the mat 2 will be confined within the cross fibers of the mat 3. The long fiber mat 2 thus provides a foundation or support for the cross fibers of the mat 3, and assures complete removal of the entire tampon, when withdrawn by manipulation of the cord 1.

The construction of the tampon, whereby the exterior surface thereof is composed substantially entirely of cross fibers, is of utmost importance, because it greatly increases the absorptive ability of the tampon and eliminates all danger of fluid flowing or leaking around the tampon, when in place, regardless of the position or activity of the wearer. Also, because of the exterior of the tampon being composed almost entirely of cross fibers, the tampon will readily and quickly expand, when subjected to the body fluids, thereby to completely fill the cavity and prevent leakage of the fluid around the tampon. The inner mat 2, being composed of long fibers extending lengthwise of the tampon, in addition to providing a support for the cross fibers of the mat 3, also provides a substantial anchor for the cord 1, as will be noted by reference to Figures 3 and 4, whereby the cord cannot become detached

from the tampon, upon removal of the tampon from the vagina.

From actual experience, it has been found that cotton provides a very desirable material for constructing the tampon. It is to be understood, however, that the inner or supporting mat 2 of the tampon may be constructed of other fibrous material applicable for the purpose. For example, bandaging gauze has been found to provide a suitable substitute for the long fiber cotton mat 2, as it provides adequate tensile strength for supporting the cross fibers of the mat 2, and also readily expands, when subjected to moisture.

The completed tampon 1, when ejected from the forming die, is very compact and has a relatively hard exterior surface, to facilitate sterilizing and packaging, and whereby it may readily and conveniently be handled before application.

I claim as my invention:

1. A method of making a tampon which comprises placing together two fibrous mats to form an elongated body, one of said mats being composed of fibers extending lengthwise thereof and the other of fibers extending crosswise thereof, whereby said body is composed of fibers arranged in crosswise relation, folding said body at a point intermediate its ends to bring the crosswise fibers into contiguous relation, and then compressing said folded body into a cylindrical shape whereby the crosswise fibers are brought to the outside of said cylindrical body and substantially conceal the lengthwise fibers.

2. A method of making a tampon which comprises placing together two fibrous mats to form an elongated body, one of said mats being composed of fibers extending lengthwise thereof and the other of fibers extending crosswise thereof, whereby said body is composed of fibers arranged in crosswise relation, folding said body at a point intermediate its ends to bring the crosswise fibers into contiguous relation, and then passing said folded body through a suitable forming die whereby the overlapped end portions of the folded mats constituting said body, are folded longitudinally in opposite directions, simultaneously as said body is compressed into substantially a cylindrical shape, whereby the crosswise fibers are brought to the outside of the completed tampon body and the lengthwise fibers concealed within the crosswise fibers.

3. A method of making a tampon which comprises placing together two fibrous mats to form an elongated body, one of said mats being composed of fibers extending lengthwise thereof and the other of fibers extending crosswise thereof, coiling a cord about the intermediate portion of said body and folding the body transversely at the cord to bring the ends of the body into juxtaposition and whereby the crosswise fibers are brought into contiguous relation, indenting opposite sides of said folded body to cause the longitudinal edges thereof to fold outwardly, and subsequently passing said body through a suitable forming die, whereby the fibers of the crosswise fiber mat are brought to the outside of the partially completed tampon and substantially conceal the fibers of the lengthwise fiber mat, said cord extending from one end of the finished tampon.

4. A method of making a relatively stiff tampon which is capable of maintaining its configuration when dry, which comprises placing together two cotton mats to form an elongated body, one of said mats being composed of fibers extending lengthwise thereof and the other of fibers ex-

tending crosswise thereof, coiling a cord about the intermediate portion of said body and folding the body transversely at the cord to bring the ends of the body into juxtaposition and

5 whereby the crosswise fibers are brought into contiguous relation, and simultaneously indenting opposite sides of said folded body longitudinally thereof, whereby the fibers of the crosswise fiber mat are brought to the outside of the partially completed tampon, and the fibers or the lengthwise fiber mat become substantially concealed within the fibers of the cross fiber mat, said cord extending from one end of the finished tampon.

15 5. A tampon comprising an elongated mat of fibrous material having its fibers running lengthwise thereof, a second mat of fibrous material having its fibers running crosswise with respect to its length, said mats being placed together in flatwise relation whereby the fibers of one mat will be disposed at right angles to the fibers of the other mat, said mats being folded about a transverse line intermediate their ends and being compressed into a self-sustaining cylindrical body, the exterior of which is composed substantially entirely of cross fibers.

6. A tampon comprising an elongated mat of fibrous material having its fibers running lengthwise thereof, a second mat of fibrous material having its fibers running crosswise with respect to its length, said mats being placed together in flatwise relation whereby the fibers of one mat will be disposed at right angles to the fibers of the other mat, said mats being folded transversely to bring their ends into juxtaposition, said folded mats being compressed into a self-sustaining cylindrical body, the exterior of which is composed substantially entirely of cross fibers, and a cord having one end secured to said body.

30 7. A tampon comprising an elongated mat of fibrous material having its fibers running lengthwise thereof, a second mat of similar size and of like material having its fibers running crosswise with respect to its length, said mats being placed together in flatwise relation to provide an elongated body having the fibers of one half its thickness running lengthwise of the body and the fibers of the other half running crosswise thereof, a cord coiled transversely about the intermediate

35 portion of said body, said body being folded upon itself at the cord in a direction to cause the end portions of the cross fiber mat to be disposed in contiguous relation, and whereby the end portions of the lengthwise fiber mat will be disposed at the outside of said folded body, and the end portions of said folded body being folded along longitudinal lines parallel to the axis of said body and in proximity thereto, whereby when said folded mats are compressed into an elongated cylindrical body, the fibers of the crosswise fiber mat will be brought to the surface and will constitute substantially the entire outer surface of the tampon, thereby rendering the tampon more absorbent.

40 8. A tampon of substantially cylindrical form comprising a U-shaped web of fibrous material the legs of such web and the fibers therein being disposed substantially parallel to the longitudinal axis of the tampon, said legs being surrounded by a fibrous web the fibers of which are generally positioned in planes which are disposed generally normal to the axis of the tampon.
